UNITED STATES PATENT OFFICE.

FRANCIS M. ROSENFELD, OF NEW YORK, N. Y., ASSIGNOR TO IMPORT SALES COMPANY,
A CORPORATION OF NEW YORK.

CIRCUIT-CLOSING DEVICE.

1,154,130.

Specification of Letters Patent. Patented Sept. 21, 1915.

Application filed January 15, 1915. Serial No. 2,305.

To all whom it may concern:

Be it known that I, FRANCIS M. ROSENFELD, a citizen of the United States, and a resident of the borough of Manhattan, city, 5 county, and State of New York, have invented certain new and useful Improvements in Circuit-Closing Devices, of which the following is a specification.

My invention relates to devices which are 10 operable manually to close electric circuits.

The object of my invention is to provide such a circuit closing device which will be inexpensive to construct, neat in appearance, easy to operate and which at the same time 15 will be protected against accidental operation.

I have illustrated my invention as applied 20 to a portable electric lamp, but it is to be understood that this embodiment is shown merely as an example of a use to which my improved circuit closing device may be put.

In the drawing, Figure 1 is a side elevation of a portable electric lamp to which my improved circuit closing device is attached; 25 Fig. 2 is a sectional view of the same; Fig. 3 is a plan view of a portion of the circuit closing device; and Figs. 4 and 5 are sectional views showing the circuit closing device in detail.

Reference numeral 6 indicates a battery or source of electric current such as is customarily used in a portable electric lamp and which is provided at its ends with the terminals 6^a and 6^b. Inclosing this battery 30 is a casing 7 constructed of fiber or other suitable material. Upon either end of the casing 7 is secured a metallic screw threaded member 8—9. The member 8 is electrically connected to the terminal 6^a of the battery through the spring 10 connected to the metallic screw threaded cap 11 which is adapted to be screwed on to the member 8. The member 9 is electrically connected to the other terminal 6^b of the battery through the filament of the lamp 12, and the metallic reflector 13. The reflector 13 and lens 14 are held in position by means of the screw threaded cap 15. The parts above described are of ordinary construction in devices of 45 this type and do not *per se* form any part of my invention.

The member 8 and consequently the terminal 6^a of the battery is electrically connected by means of the conductor 16 to the 50 guide member 17. This guide member 17

may be of metal or other conducting material and is secured to the exterior of the casing 7 by means of the rivets 18 and 19, the rivet 18 serving also to electrically connect the guide member 17 to the conductor 16. This guide member 17 is provided with two openings therethrough, 20 and 21. In the opening 20 is the rivet 22 which serves as a stationary contact and also to hold the conductor 23, located on the interior of the casing, in position. This conductor 23 serves to connect the rivet 22, or stationary contact with the terminal 6^b of the battery through the reflector 13 and the lamp filament. It is to be noted, see for instance Fig. 3, that the 60 contact member 22 is insulated from the guide member 17 by reason of the opening 20. Also it should be noted that by reason of the opening 24 in the conductor 23 the rivet 19, which is electrically connected to the guide member 17, is insulated from the 65 conductor 23. Slidably mounted on the guide member 17, as shown in Fig. 5, is the 70 sliding contact member 25. This sliding contact member is made of metal or other 75 conducting material and is normally connected to the terminal 6^a of the battery through the guide member 17, rivet 18, conductor 16, etc. When in normal position, however, the sliding contact member 25 is 80 insulated from the stationary contact member 22, which is, as has been stated, connected to the other terminal battery. To insure proper insulation the sliding contact member is provided on the surface thereof, which 85 is adjacent to the stationary contact member 22, with an indentation 26, as clearly shown in Fig. 4. The forming of this indentation 90 on the inner surface of the sliding contact member serves to form also a corresponding 95 projection 27 on the other or outer surface thereof, which is useful as a thumb piece by means of which the sliding contact member may be operated. The sliding contact member 25 is also provided with a projection 100 28 on the surface thereof which is adjacent the stationary contact member. This projection 28 normally rests in the opening 21 of the guide member and serves to lock the sliding contact member in normal position. 105 To close the circuit through the battery and lamp filament, it is merely necessary to move the sliding contact member to the left, as shown in Fig. 4, by a pressure of the thumb on the projection 27. This moves the pro- 110

jection 28 into contact with the stationary contact member 22 and thus closes the circuit. Projection 28, while in contact with the stationary contact member 22, will also rest in the opening 20, thus serving to lock the slidable contact member in operated position. The slidable contact member may be returned to normal position by a pressure of the thumb on the left hand side of the projection 27, as shown in Fig. 4, or by placing the thumb partially into the depression 29 formed on the exterior of the slidable contact member and corresponding to the projection 28 on the interior thereof. The slid-
able contact member may be bent over at its ends or provided with suitable projections such as are shown at 30 in the drawing to limit its movement with respect to the guide member 17.

The operation of my improved circuit closing device should be apparent from the above description. The simplicity of my device is a great advantage, since it is practically impossible for it to get out of order or for it to be accidentally operated. Also the expense of the manufacture is reduced to a minimum. For example, it is to be noted that the rivet 18 serves to secure both the guide member 17 and the conductor 16 in position and to electrically connect these two elements. Again the rivet 22 serves as the stationary contact member and also serves to retain the conductor 23, to which it is electrically connected, in position. Of the three rivets, the rivet 19 alone serves but one purpose, namely, to retain the guide member 17 in position. The fact that my improved device is small in size and substantially flat is also an advantage for obvious reasons.

While I have described a particular embodiment of my invention and one used in connection with a particular type of device, I do not wish to be limited by my disclosure and description, since obviously many changes may be made in my improved circuit closing device by those skilled in the art, without departing from the spirit of the invention.

What I claim is:

1. In a portable electric lamp, a battery inclosing casing, a fixed guide secured to and substantially flush with the exterior surface of said casing and provided with an opening therethrough, a fixed contact member located in said opening and connected to one terminal of the battery circuit and a

slidable contact member mounted on said guide in juxtaposition to said fixed contact member and normally insulated therefrom, but adapted when operated to contact therewith.

2. In a portable electric lamp, a battery inclosing casing, a fixed guide secured to and substantially flush with the exterior surface of said casing and provided with an opening therethrough, a fixed contact member located in said opening and connected to one terminal of the battery circuit and a slidable contact member mounted on said guide in juxtaposition to said fixed contact member and provided with an indentation in the surface thereof adjacent to said fixed contact member, whereby the slidable contact member is normally insulated from the fixed contact member, said slidable contact member being adapted when operated to contact with the fixed contact member.

3. In a circuit closing device, a fixed guide provided with an opening, a fixed contact member located in said opening, and a slidable contact member mounted on said guide in juxtaposition to said fixed contact member, and normally insulated therefrom, said slidable contact member being provided with a projection on the surface thereof adjacent the fixed contact member and adapted to contact therewith when the slidable contact member is operated, and to rest in said opening to lock the slidable contact member in operated position.

4. In a circuit closing device, a fixed guide provided with an opening, a fixed contact member located in said opening, and a slid-
able contact member mounted on said guide in juxtaposition to said fixed contact member, and normally insulated therefrom, said slidable contact member being provided with a projection on the surface thereof adjacent the fixed contact member and adapted to contact therewith when the slidable contact member is operated, and to rest in said opening to lock the slidable contact member in operated position, said fixed guide being provided with another opening in which said projection is adapted to rest to lock the slidable contact member in normal position.

In testimony whereof I have signed this specification in the presence of two subscribing witnesses.

FRANCIS M. ROSENFELD.
